UNITED STATES PATENT OFFICE.

BARTOW KOOPMAN, OF NEW YORK, N. Y., ASSIGNOR, BY MESNE ASSIGNMENTS, TO
PARAMOUNT FUEL OIL BURNER CO., A CORPORATION OF NEW YORK.

OIL BURNER.

Application filed August 22, 1923. Serial No. 658,680.

My invention relates to oil burners adapted for burning the cheaper oil commonly known as fuel oil and gas oil, for heating purposes. While the burner is not limited 5 in its use, I have found it very effective for heating boilers such as are used in heating plants for heating dwellings and other buildings. The present device is simple and efficient and without great expense it 10 may be applied to boilers at present equipped for burning coal so that a change may be readily made for utilizing liquid fuel in place of coal. Not only is the liquid fuel economical for heating purposes but 15 the present burner requires very little attention as compared with a coal fire, and uniform temperatures may be maintained.

The device consists of a cone shaped oil container and gravity feed arrangement together with a cone shaped flame deflector; and suitable means for supplying air to the flame and for easily regulating the proportion of air to provide for most efficient operation.

25 In the drawings forming part of this application,

Figure 1 is an elevation of my device showing the same partly in vertical section,

Figure 2 is a sectional view taken on the 30 line 2—2 of Figure 1,

Figure 3 is a sectional view taken on the line 3—3 of Figure 1, and

Figure 4 is an elevation of the air shutter.

I have shown my burner placed in the 35 fire chamber of an ordinary house steam boiler. The fire chamber 1 is surrounded by the water jacket 2 which is in communication with the large tank 3 extending upwardly from the heating plate 4 above the fire box. The burner as herein shown comprises a metal head 5 having a cylinder 6 extending downwardly therefrom and the whole device is adapted to be supported upon the coal grate or upon suitable supports upon which the extending plugs 7 40 may be bolted to the supports 42 by means of vertical bolts 43. The head has an annular flange 8 extending upwardly therefrom and seated in suitable slots 9 in this flange are the vertical posts 10 which support the deflector 11 at some distance above the head 5. This deflector 11 is flared upwardly and outwardly from the point 12 in more or less cone shape the outer edges 13

of the deflector terminating sufficiently near 55 the inner wall 14 of the boiler to cause the flame to be deflected against this wall and to pass upwardly around the deflector to heat the plate 4. Preferably, the deflector is provided with a number of perforations 15 in 60 order to minimize the warping of the deflector. The burner proper comprises a cylindrical wall 16 surrounded by a conical wall 17 which form between them an annular chamber 18 for the oil, which decreases in 65 width gradually toward the top where I provide a number of outlet ports 19 for the liquid fuel to pass into the tray 20. The latter, which is shown as annular, and inclined downwardly from the ports 19, is provided with a number of upturned annular flanges 21, 22, 23, forming grooves 24 for holding the oil which flows out of the ports 19. These flanges are provided with slots 25 to permit the oil to flow from one groove 24 to another and in order to compel the oil 70 to spread out through these grooves, I provide the slots 25 in the flange 21 at points remote from the slots in the flange 22. The lower flange 23 has no slot and if the oil 75 flows above the edge of this flange it falls into the chamber 26 and some of it is held by the priming wick 27 which surrounds the lower part of the burner wall 17. The remainder accumulates in the chamber 26 80 and flows back through the pipe 27 into a suitable receptacle, not shown, or to the reservoir from which the oil is being fed. It 85 will be understood, however, that when desired the grooved formation of the tray may be dispensed with and the oil during the initial operation which flows from the lateral ports 19, discharges into the combustion chamber 26. After a predetermined amount of oil accumulates within the combustion 90 chamber 26 the valve 34 is closed to prevent a further ingress of the oil in the combustion chamber. The oil within the combustion chamber is then ignited and the necessary 95 air to support combustion is provided by the air passage 39. The valve 34 is thence again opened and oil permitted to flow through the fuel member 18. The burning of the oil in the combustion chamber serves to intensely heat the fuel member 17 and to thereby 100 convert the oil therein into gas so that a continued operation of the apparatus will 105 result in a continuous flame at the ports 19,

By forming the ports 19 laterally with respect to the vertical axis of the fuel member, there is less danger of the ports becoming clogged up with carbon or other extraneous 5 impurities contained in the crude oil. It will be understood that at first the flame emitting from the ports 19 may be weak and the primary purpose of the element 21 is to prevent the extinguishment of the flame by 10 the air admitted through 39. The chamber 26 is formed by an annular wall 28 extending upwardly from the plate 29 and it is open at the top. The plate 29 is separated from the head 5 by means of the several 15 vertical posts 30 depending from the head 5. The oil is fed from a reservoir 31 by gravity through the pipe 32 to the connection 33 which admits the oil to the lower part of the chamber 18 and the feed of the 20 oil is regulated by a needle valve 34. Resting on the lugs 35 on the head 5 there is an annular ring 36 which has inclined resting edges 37 which rest upon the lugs 35 and this member also has oppositely disposed 25 projecting ears 38 which may be engaged by a suitable tool for the purpose of turning the shutter member 36. By turning this shutter member around to the right or left it may be caused to rise or fall according 30 to the portions of the inclined edges 37 which engage the lugs 35. This shutter member projects downwardly within the upwardly extending wall 28 and it is spaced therefrom to form an air passage 39 whereby the air 35 may pass around the top edge of the wall 28 thence under the bottom edge of the shutter 40 and thence upwardly around the tray member 20 where it commences to mix with the flame and provide oxygen to support 45 combustion. The air entering in this manner may be increased by adjusting the shutter to a higher position and it may be decreased by lowering the shutter to a lower position and in this manner the proportion 50 of air may be regulated to suit the requirements of the particular fuel which is being burned. Below the plate 29 there is an inverted cone or head 41 in which air may rise upwardly through the tube 42 placed 55 inside the hollow burner wall 16 and this air emerges at the point of the cone deflector and at the top of the burner so that it mixes with the interior of the annular shaped flame. This air also serves to provide 60 a current which will assist in carrying the flame along the under side of the deflector.

Operation.

The wick 27^a employed as a primer is 60 lighted and the flame rises upwardly to ignite the oil on the tray 20. The needle valve 34 is opened and the oil flows from the reservoir 31 through the pipe 32 into the chamber 18. It rises in this chamber to the upper and narrow portion where it flows out 65

through the ports 19 onto the tray 20, filling the several grooves 24. When the oil is spread out on this tray the flame from the priming wick 27^a ignites the oil and the flame rises upwardly, being combined with the air entering through the tube 42 and the flame is deflected by the deflector 11 outwardly and against the wall 14 of the boiler. The flame passes around the outer edge of the deflector and spreads across the plate 4 70 so that the water in the boiler is very rapidly raised to a point where steam is generated. After steam has been generated in the boiler the needle valve 34 will be regulated to maintain the desired steam pressure in the boiler 75 and no further attention need be given to regulation over considerable periods of time unless a change in weather conditions requires an increase or decrease of boiler temperature. When the burner is in operation the shutter 40 may be regulated by turning it to the left or right for the purpose of increasing or decreasing the proportion of air supplied to the burner in order 80 that the fuel will receive the proper proportion of oxygen to support efficient combustion. If at any time the oil is fed through the ports 19 upon the tray 20 faster than it is consumed in combustion, the excess oil 85 will flow off the tray 20 and fall into the chamber 26 where it is drawn off through the pipe 27.

As heretofore stated, it is perhaps the preferred manner of practicing the invention to permit oil to initially descend to the combustion chamber 26 and to be fired therefrom; thereafter to again open the valve 34 to permit oil to enter the space 18 where it is converted into gas by the burning of the fuel from the combustion chamber with the result that there is a constantly discharged flame emitted from ports 19. The ports 19 are preferably protected by an annular plate 22, which for the purpose of description has been termed a "tray". This term, however, is used as a word of description and not of limitation and this element can be any kind of a deflector to prevent extinguishment of the weak flame emitting from ports 19 by the air passing around through the channel 39. 105

It will be apparent that the present device is very simple and rugged in construction and that it may be very readily placed in the fire boxes of steam boilers at present heated by coal fuels. 110

Having described my invention what I claim is,—

1. In an oil burner a member comprising walls forming an annular fuel chamber having outlets in its upper portion, an annular plate arranged under said outlets and an air shutter comprising annular members surrounding said member, one of said annular members being inverted in relation to the other and projecting downwardly therein, 115

said annular members being of different diameters whereby a space is formed between them for the passage of air to the fuel member.

5 2. In an oil burner a member comprising walls forming an annular fuel chamber having outlets in its upper portion, an annular plate arranged under said outlets and an air shutter comprising annular members surrounding the said member, one of said annular members being inverted in relation to the other and projecting downwardly therein, said annular members being of different diameters whereby a space is formed between them for the passage of air to the fuel member, and means for regulating one of said annular members to vary the extent to which one of the annular members projects within the other.

10 3. In an oil burner a member comprising walls forming an annular fuel chamber having outlets in its upper portion, an annular plate arranged below said outlets, means forming an oil chamber around said member below said tray and including an upwardly extending flange forming part of an air shutter, an inverted annular member surrounding said fuel member and extending within said first flange and spaced apart laterally therefrom whereby air may enter by passing over said lower flange and under said annular member and inclined supports for said annular member whereby the latter may be adjusted to extend varying distances within said lower flange.

4. In an oil burner a member comprising walls forming an annular fuel chamber having outlets in its upper portion, an annular plate arranged below said outlets, means forming an oil chamber around said member below said annular plate and including an upwardly extending flange forming part of an air shutter, an inverted annular member surrounding said fuel member and extending within said first flange and spaced apart laterally therefrom whereby air may enter by passing over said lower flange and under said annular member, inclined supports for said annular member whereby the latter may be adjusted to extend varying distances within said lower flange, said annular member having an inclined outer surface whereby the lateral space between said flange and said annular member will be varied as the height of the annular member is varied.

5. In an oil burner a member comprising annular walls forming an annular oil chamber having an opening therethrough for the passage of air, said chamber having lateral outlets in its upper portion, an annular plate arranged below said latter outlets, and means forming an oil holding chamber around the bottom of said member whereby oil may be burned in said lower chamber for

priming purposes to heat said fuel member. 65

6. In an oil burner a member comprising walls forming an annular chamber having outlet ports in its upper portion, an annular plate arranged below said outlets, means forming an oil chamber adjacent the bottom portion of said member and including an upturned flange, an annular member cooperating with said flange whereby said members extend one within the other in laterally spaced relation whereby air may pass over the edge of one of said members and under the edge of the other to the fuel member. 75

7. In an oil burner of the class described, a nozzle comprising walls forming an annular fuel chamber having a lateral outlet at its upper portion, a deflector plate arranged under said outlet to prevent extinguishment of the flame emitting therefrom, said nozzle having a central primary air supply, means for feeding a secondary supply of air to said fuel outlet, an air shutter for limiting the supply of the secondary air to the fuel outlet, and means for conveying oil to said fuel chamber. 85

8. In an oil burner of the character described, comprising a nozzle having walls forming an annular fuel chamber, lateral outlets in the upper portion of said fuel chamber, a deflector mounted upon said nozzle at a point below the outlets, a central air passage for said fuel nozzle for conveying a primary air supply thereto, means for feeding a secondary supply of air to said fuel nozzle, and an air shutter associated with said nozzle and adapted to variably regulate the supply of secondary air to said fuel nozzle. 90 95

9. In an oil burner, a nozzle member comprising walls forming an annular fuel chamber having lateral outlets at its upper portion, a deflector element mounted upon said nozzle at a point below the outlets, an air shutter comprising annular members surrounding the fuel nozzle, said annular members being of different diameters whereby a space is formed between them for the passage of secondary air to the fuel member. 105 110

10. In an oil burner, a nozzle member comprising walls forming an annular fuel chamber having lateral outlets at its upper portion, a deflector element mounted upon said nozzle at a point below the outlets, an air shutter comprising annular members surrounding the fuel nozzle, said annular members being of different diameters whereby a space is formed between them for the passage of secondary air to the fuel member, one of said annular members being adjustable to variably control the supply of secondary air to said fuel member. 115 120 125
